UNITED STATES PATENT OFFICE.

GEORGE K. BRENNER, OF PORTERVILLE, KANSAS.

DISK CULTIVATOR.

SPECIFICATION forming part of Letters Patent No. 603,167, dated April 26, 1898.

Application filed November 28, 1896. Serial No. 613,758. (No model.)

To all whom it may concern:

Be it known that I, GEORGE K. BRENNER, a citizen of the United States, residing at Porterville, in the county of Bourbon and State of Kansas, have invented certain new and useful Improvements in Disk Cultivators; and I do hereby declare the following to be a full, clear, and exact description of the invention, such as will enable others skilled in the art to which it appertains to make and use the same.

My invention relates to disk cultivators.

My object is to provide a cultivator of the class described which will be composed of but few parts and be light and strong and one of such peculiar construction that the disks can be easily adjusted by the driver to suit the requirements of the occasion.

Having this object in view, the invention consists of a disk cultivator comprising those novel features and combinations of parts appearing more in detail hereinafter.

In the accompanying drawings, Figure 1 is a side elevation, Fig. 2 a rear view, Fig. 3 a plan view, and Fig. 4 a perspective view, of the complete machine.

The draft-tongue is designated by the numeral 1, and at the rear of this draft-tongue there is a driver's seat 2, while the machine is mounted on suitable traction-wheels 3.

30 The numeral 4 designates an adjustment-box which is in the shape of a casting, connected to the rear portion of the draft-beam underneath the latter.

5 and 6 indicate two L-shaped frame-pieces or horizontal bars, which have their adjacent ends secured in openings or sockets in the opposite ends of the adjustment block or box 4, the arrangement being such as to allow said frame-bars to rock in said sockets or openings.

40 When it is desired to hold the bars at any fixed adjustment, it is done by means of set-screws 7 and 8, which serve to prevent end-wise movement of the frame-bars, but which when loosened permit the frame-bars to be rocked in their bearing in the adjustment box. The pendent rigid arms at the outer ends of these frame-bars extend down through perforations in the boxes 17 and 18, in which the disk-shafts 13 and 14 are journaled, the arrangement being such as to give the shafts a swiveling connection with said pendent arms.

9 and 10 indicate pendent arms intermediate the adjustment-box 4 and the outer rigid arms of the frame-bar and sleeved upon the horizontal portions of said arms or otherwise pivotally connected therewith to allow them to swing independently of the rigid pendent arms of said frame-bars. These pendent arms 9 and 10 extend through the boxes in which the disk-shafts 13 and 14 are journaled, the said boxes having a swiveling connection with the lower ends of said pivoted arms 9 and 10, the arrangement being such that the ends of the shaft supported by the swiveling or pendent arms 9 and 10 may be vibrated independently of the rigid pendent arms of the frame-bars for swinging the shafts into alinement or into different angles of relation to a transverse line.

15 indicates a series of disks carried by one shaft, and 16 a series carried by the other shaft.

19 and 20 indicate scraper-bars carried by the respective sets of boxes in which the shafts 13 and 14 are journaled.

21-21 indicate converging rods connected at their rear ends with the lower ends of the rigid pendent arms of the frame-bars and converging thence forward, where they pass through a horizontal slot in the tongue indicated at 22. The tongue is also provided with a guide-slot 23.

The numeral 24 designates a cross-beam which has a pivot-bolt 25, that passes through the slot in the tongue and is adapted to move therein. It is not clamped at any point, so it will be seen that this beam has an adjustable pivot—that is to say, the beam can be moved longitudinally in relation to the tongue and yet at all times be pivoted so that it may swing horizontally.

The numeral 26 designates a rearwardly-extending shifting lever which has its forward end rigidly connected to the cross-beam, and this lever has a dog adapted to ride on and engage with a transverse rack 27, whereby the lever may be locked.

The numeral 28 designates a controlling-lever of ordinary construction, which is pivoted to that portion of the rod 21 that is journaled in the frame and has its lower extremity pivoted to the tongue. This controlling-lever is connected to the cross-beam.

The numerals 29 and 30 designate rods which connect the ends of the cross-beam with the lower portion of the supplemental frame-pieces.

5 At 31 there is shown a foot-rest for the driver, which can be raised or lowered, as desirable.

The operation is extremely simple and as follows: When it is desired to give inclination to the cultivator-disks, the shifting lever can be moved and said disks and their shafts will be inclined to any desired degree, as the lever can be locked at any point. If it is desired to raise and lower the disk-shaft and disks, the controlling-lever can be moved either forwardly or backwardly, as the case may be, thereby rocking the horizontal arms of the L-shaped frame-pieces in their sockets in the block or adjustment-box by the simultaneous forward or backward movement of both the rigid and the swinging pendent arms of the disk-supporting frame.

Having thus described the invention, what is claimed as new is—

25 1. In a wheeled disk cultivator, the combination with the draft-beam, of the disk-supporting frames pivotally connected therewith and having each a pendent rigid arm and a pendent arm, adapted to swing on the horizontal frame-arm the disk-shafts having a swiveling connection with said arms, an adjustable cross-bar connected with the pendent swinging arms for simultaneously swinging the disk-shafts on the rigid arms for adjusting the angle of presentation of the disks, and means for adjusting said cross-bar longitudinally upon the machine.

2. In a wheeled disk cultivator, the combination with the disk-shafts and disks carried thereby, of overhanging frames pivoted to swing in a vertical plane and having pendent rigid arms pivoted to the disk-shafts, supplemental suspending arms pivotally connected to the disk-shafts and also pivoted at points 40 in alinement with the pivotal points of the sus-

pending frames, means for swinging the suspending frames forwardly and upwardly, and independent means for swinging the supplemental arms independently of the suspending frames, whereby the disk-shafts can be 50 simultaneously set at any desired inclination to a transverse line.

3. In a disk cultivator, the combination with depending frame-pieces adapted to swing upwardly, of supplemental pivoted members, 55 sets of cultivator-disks carried by the main frame-pieces and the supplemental members, rods connected to the frame-pieces and movable longitudinally of the machine, a controlling-lever connected to said rods for operating said frame, a pivoted cross-bar, rods connecting the same to the supplemental members, a shifting lever adapted for lateral movement and to which the controlling-lever is pivoted, and means for locking the said shifting lever.

4. In a wheel disk cultivator, the combination with the pendent rigid arm of the supporting-frame pivoted to swing forwardly and upwardly, of supplemental members pivoted 70 to the frame-piece and also adapted to swing forwardly and upwardly, disk-shafts pivoted to the frame-piece and to the supplemental members, disks carried by said shafts, a cross-bar pivotally connected with and movable 75 longitudinally of the machine, a controlling-lever having its extremity pivoted to the main frame and which is also pivoted to the cross-bar, rods connecting the ends of said cross-bar and the supplemental members, a shifting lever secured to the cross-bar for adjusting the angle thereof, and means for locking said lever at any desired adjustment.

In testimony whereof I have signed this specification in the presence of two subscribers.

GEORGE K. BRENNER.
